CONTAINERS FOR MATERIAL IN BULK

This invention is concerned with containers for transporting, storing or handling materials (e.g. powdered, granular or pulverulent materials or liquids) in bulk.

Containers for bulk materials are known having a hopper bottom with an outlet to enable complete discharge of the contents. Such containers usually comprise a vessel and a supporting frame. It is an object of the present invention to provide an improved form of such a container in which a damaged vessel or frame can readily be replaced.

According to the invention, there is provided a container for materials in bulk, said container comprising a vessel with a body portion and at the lower end of the body portion a hopper tapering to a discharge outlet, and a supporting framework detachably secured to the vessel, said framework including an upper portion engaging around the hopper adjacent the junction thereof with the body portion and providing a seat which vertically and laterally locates the vessel and a lower portion engageable with the ground to support the container thereon.

Preferably, said upper portion of the framework has inclined flanges engaging the hopper and upright flanges surrounding the lower end of the body portion of the vessel.

The hopper preferably has outwardly extending flanges which are detachably secured to anchorages within the framework. The outwardly extending flanges are preferably integral with the hopper and preferably lie in vertical planes.

The body portion of the vessel is preferably of rectangular form and the hopper is preferably of four-sided pyramidal form. Preferably, the framework has four feet corresponding to the corners of the body portion and vertical support members extend between the feet and said upper portion of the framework.

The vessel may have a hopper at each end, with means for detachably securing the vessel to the framework on reversal of the vessel.

The following is a description, by way of example, of bulk material containers in accordance with the invention, reference being made to the accompanying drawings, in which:

FIG. 1 is an exploded perspective view of a container;

FIG. 2 is a top plan view of the container of FIG. 1;

FIG. 3 is a side elevation of the container of FIG. 1;

FIG. 4 is a side elevation of a modified container; and

FIG. 5 is a top plan view of the container of FIG. 4.

Referring first to FIGS. 1 to 3, the container comprises a vessel having a general rectangular body portion 1 with a top 2 having a central filling opening 3 which can be closed by a suitable lid (not shown.) The top 2 is formed at its corners with recesses 4. At the lower end of the body portion 2, the vessel is provided with a hopper 5 of four-sided pyramidal form. The hopper has at its bottom a discharge outlet 6 fitted with a suitable valve (not shown). The four corners of the hopper are provided with outwardly extending integral flanges 7 which lie in vertical planes and which have bolt holes 8.

The vessel is detachably secured (by bolts as hereinafter described) to a rectangular supporting framework 9 which surrounds the hopper and comprises an upper generally rectangular frame part 10, a lower corresponding generally rectangular frame part 11 and interconnecting vertical members 12 secured between the frame parts 10 and 11. The upper frame part 10 has inclined flanges 10a engaging around the hopper and upright flanges 10b surrounding the lower part of the body portion 1 of the vessel and thus provides a seat which vertically and laterally locates the vessel. The lower frame part

11 is braced by horizontal struts 13. Feet 14 are provided at the corners of the frame part 11 and are arranged to fit the recesses 4 in the top of another similar container so that the containers can be stacked on top of one another. The feet provide sufficient clearance between the frame part 11 and the ground (or the top of another container) for insertion of a fork lift to engage beneath the frame part 11 and lift the container. Brackets 15 are welded to the vertical members 12 and project diagonally inwards therefrom, the brackets 15 having bolt holes 16 corresponding to the bolt holes 8, the arrangement being such that bolts 17 can be passed through the holes 8 and 16 and fastened in position by nuts 18 having washers 19 associated therewith. Thereby, the vessel is detachably secured to the framework.

15 The modified container shown in FIGS. 4 and 5 is substantially identical in construction to that of FIGS. 1 to 3 except that the top 2 is replaced by a hopper 5' similar to the hopper 5 and having flanges 7' with bolt holes 8' and, at its top, an inlet 6' corresponding to the outlet 6. Thus, the vessel can if desired be reversed in the framework 9. Also, if desired the container can be tilted to discharge through the inlet 6'.

20 The vessel may, for example, be made from aluminum alloy or mild steel sheet, while the framework may be made of mild steel angle.

25 In the event of damage to the vessel or the framework, the damaged member can readily be removed and replaced and maintenance of the containers in good working condition is thereby facilitated and made more economical.

I claim:

30 1. A container for materials in bulk, said container comprising a vessel having a body portion of rectangular boxlike form with the lower end thereof tapering to form a four-sided pyramidal hopper serving as a discharge outlet, and a supporting framework detachably secured to the vessel, said framework comprising an upper portion having inclined flanges engaging the hopper and upright flanges surrounding the lower end of the body portion of the vessel, and a lower portion comprising horizontal framework members with at least four ground-engaging feet depending therefrom, said feet 35 providing clearance between the ground and the horizontal members of the framework for insertion of a forklift to engage the horizontal members and lift the container.

40 2. A container according to claim 1, further comprising vertical support members extending between the horizontal members and said upper portion of the framework, integral outwardly extending vertical flanges on the hopper, and anchorages fixed on the vertical support members and detachably secured to said flanges, said anchorages and flanges being disposed wholly within the confines of the framework so as to be thereby protected from damage.

45 3. A container according to claim 2, further comprising recesses in the top of the vessel at its corners corresponding to the four feet, whereby the container is stackable.

50 4. A container for materials in bulk, said container comprising a vessel with a body portion and at the lower end of the body portion a hopper tapering to a discharge outlet, and a supporting framework detachably secured to the vessel, said framework including an upper portion detachably engaging around the hopper adjacent the junction thereof with the body portion and providing a seat which vertically and laterally locates the vessel and a lower portion engageable with the ground to support the container thereon, the upper end of the vessel having means for detachably securing the vessel to the framework on reversal of the vessel relative to the framework.

55 5. A container according to claim 4, wherein the vessel has a hopper at each end.

UNITED STATES PATENT OFFICE
CERTIFICATE OF CORRECTION

Patent No. 3,602,400 Dated August 31, 1971

Inventor(s) Arthur H. COOKE

It is certified that error appears in the above-identified patent and that said Letters Patent are hereby corrected as shown below:

The assignees name should correctly read ALCOA CONTAINERS SYSTEMS (GB) LIMITED, of West Hill, Blackdown, Leamington Spa, Warwickshire, England.

Signed and sealed this 28th day of March 1972.
